US00D595597S

(12) **United States Design Patent**
Meverden

(10) **Patent No.:** **US D595,597 S**
(45) **Date of Patent:** **** Jul. 7, 2009**

(54) **GPS LOCATION TRANSMITTER**

(76) Inventor: **Bradley P. Meverden**, N10441 Maple Rd., Birnamwood, WI (US) 54414

(**) Term: **14 Years**

(21) Appl. No.: **29/310,701**

(22) Filed: **Sep. 5, 2008**

(51) LOC (9) Cl. **10-04**

(52) U.S. Cl. **D10/65**

(58) **Field of Classification Search** D10/65, D10/78; D14/347; 342/351, 419, 457, 357.06–357.13; 343/702; 345/87, 104, 133, 156, 168, 173, 345/901–905; 348/180, 184, 315, 739; 364/444, 364/499; 701/206–209, 213, 214

See application file for complete search history.
